TIPPLER APPARATUS.

Hatsujiro Fujishige, Onoda City, Japan

Application July 21, 1955, Serial No. 523,508.

7 Claims. (Cl. 214—52)

The present invention relates to a tippler apparatus.

An object of the present invention is to provide an automatic tippler apparatus, in which the construction is simple and the handling made easy.

Another object of the present invention is to provide a tippler apparatus in which the coal contained within a set of tubs, is dumped under pull of a winding rope without necessitating any special additional appliances and the handling of the empty tubs is performed smoothly.

A further object of the present invention is to provide a tippler apparatus in which driving of a winch from which one end of the rope extends around and over a pulley and is fastened to one set of tubs, will cause rotation for discharging coal in each tub set held in position on the rail within a rotatory framed structure, will provide return motion of the said framed structure, and, wherein the handling of empty tubs, by winding out said rope and other operations, are all effected automatically.

Other objects, features and advantages of the present invention will be apparent from the following description.

In the known types of tipplers, a set of coal tubs or coal cars are fed horizontally into the tippler by means of a pusher, held in position by some braking device and then tipped to discharge the coal therein. Further, the empty tubs have to be shifted transversely out of the way of the following set of tubs. Thus, in such a tippler not only additional appliances are needed but also there is a disadvantage in that some tubs, coupled by pins, might become disengaged.

The present invention is concerned with an improved tippler or tippler apparatus in which the defects, as above described as occurring in the tipplers heretofore in use, are eliminated. The tippler or tippler apparatus according to the present invention comprises a rotary framing or a rotatory framed structure with its top open. Both side walls of the framing are formed of steel plates secured to frame members or to a portion of such frame members and a rail for coal tubs is laid at the bottom of said framed structure. The rotary framing or framed structure is positioned above a coal bin or stacking yard with a desired longitudinal inclination, and to the outside of the framed structure, are respectively secured, at a proper spaced distance, frame-supporting rings having respectively a peripheral protrusion and sprocket rings formed respectively with sprockets or wave-shaped teeth along the whole or a part of the groove on its periphery for engaging with links of a chain. The supporting rings are preferably secured at the ends of the framing or the framed structure and the sprocket rings are secured at equal spacings between these supporting rings, each of which rotatably rests at its bottom on two grooved rollers, one for each side, and are held respectively in position by a pair of corresponding stops. An endless chain is passed around the wave-shaped teeth

2

or sprockets of each of said sprocket rings and around each of the small sprocket wheels mounted on the axle of a driving electric motor. The inclination or angle at which said rotary framing or framed structure may be set, may be between the minimum of about two degrees and the maximum of about twenty degrees, preferably at about two or three degrees for the normal condition.

Coal tubs are pulled up in sets, each consisting of several, say, six tubs coupled together, into the rotary framing by winding up a rope over a pulley by means of a winch. The rotary framing is then rotated, with the tub set held therein, under pull of said rope, for a proper angle, for example, of about 100 to 180 degrees, depending upon the qualities, sizes and the like of the coal to be discharged. The framing is kept in this tilted position for a moment, say, two or three seconds, and subsequently restored to its original position by reversing the driving of the chain, whereupon the rope is let out, allowing the empty tubs to descend onto a siding, all these operations being effected automatically. Accordingly, it is possible in this tippler to handle coal tubs very effectively and accurately with simple operation, and also to discharge the coal automatically out of the tubs, without necessitating any special additional appliances. Also, in the tippler according to the present invention, each rotary framing is carried rotatably at its supporting ring upon rollers on both sides with a suitable inclination, so that a downward force due to gravity along the surface of the railing, is always acting on the tub set held in position on the rail in said framed structure by the rope, thus both the rope itself and the couplings between tubs being kept rigid. The tension serves to keep the aforesaid couplings engaged throughout, even when the framed structure is turned to roll the tubs over, and to cause the coal to be dumped under pull of the rope, so that the empty tubs are handled smoothly.

In order that the invention may be more clearly understood reference will now be made to the accompanying drawings which show by way of example a preferred embodiment thereof.

In the drawings:

Fig. 1 is a side view of a tippler apparatus according to the present invention;

Fig. 2 is a plan view thereof;

Fig. 3 is a plan view thereof showing the way in which coal tubs are shunted;

Fig. 4 is an enlarged vertical sectional view showing the main part of a rotary framed structure of the tippler apparatus according to the invention with one of its side walls removed;

Fig. 5 is a fragmentary plan view of a detail of the tippler on an enlarged scale;

Fig. 6 is a perspective view of a part of the rotary framed structure and

Fig. 7 is a vertical cross sectional view of the tippler taken on the line VII—VII of Fig. 5.

Referring to the drawings, a rotary framing or rotary framed structure A comprises a framed structure arranged above a coal bin or stacking yard at a suitable longitudinal inclination or slope of, for example, 2 or 3 degrees. Both side walls of the framed structure are formed of steel plates 1 secured to frame members 2 or a structure of such frame members 2. On the outside of the rotary framing or the framed structure are, at proper intervals, attached supporting rings 4 having respectively a peripheral protrusion 3 and sprocket rings

5 formed respectively with wave-shaped teeth or sprockets 6 along the whole or a part of the groove provided on its periphery. Each of the said supporting

rings rests rotatably, at its bottom, on two grooved rollers 7-7, one for each side, and is held longitudinally in position by a pair of stops 26 provided respectively adjacent the lowest central portion of the supporting ring 4 in such a manner that these stops embrace respectively the said lowest central portion and retain the framed structure A in longitudinal position. Each of said sprocket rings 6 are carried, at its bottom, on two grooved rollers 27, one for each side. An endless chain 10 is respectively passed round the wave-shaped teeth or the sprocket 5 of the sprocket rings 6 and around a small sprocket wheel 9 mounted on the extension of the axle of a driving electric motor 8, whereby said sprocket rings 6 rotate, freely clockwise or counterclockwise. In the circuit of said electric motor 8, are inserted a starting switch 11 and a limit switch 12. The limit switch 12 initiates operation of the motor 8 with the tubs in position in the rotary framing and may be responsive, in known manner, to some physical action such as the operation of the winch 15 hereinafter described. Coal tubs are drawn up on a main rail 13 laid at an inclination of about three degrees in sets, each consisting of several, for example, six tubs. A rope 14 connected at one end to the front end of the foremost tub is secured at the other end round a winch 16, passing over a pulley 15. In the circuit of another electric motor 17 for said winch 16 are inserted an operating button switch 18 and a limit switch 20. The limit switch 20 may also be responsive to winch 15 in known manner. When after connecting the lower end of the rope 14 to the foremost tub (B) on the main rail 13, the winch 16 is operated by closing the hand switch 18, and thereby the set of tubs is pulled up into position on a rail 19 laid at the bottom of the rotatory framing (A), the winch operates automatically by means of the automatic switch 20. At the same time the starting switch 11 is closed to start the driving motor 8, whereby the sprocket wheels 9 are respectively driven to rotate the rotatory framed structure (A) through the chain 10 by, say, 180 degrees, said framing or framed structure being kept in that angular position for a few seconds so that the coal in the tubs can be discharged completely. Therefore, at the moment the framing is caused to returned to its original position by being turned in the opposite direction, the limit switch 20 acts to drive the winch 16 in reverse so that the rope 14 is let out, allowing the empty tubs to descend over the self-acting said switches 21 onto a siding 22. The lower end of the rope 16 is then transferred from the set of empty tubs to the following set of full ones on the main rail 13 and, thus the aforesaid operations may be repeated. Immediately below the central part of the rotary framing (A) is provided a coal bin 23. In front of and behind the bin are arranged a hopper 24 and a conveyor 25 which is below the front as well as rear part of the rotatory framing, so that all the coal discharged from tubs may be gathered in the coal bin 23.

According to this invention, the tubs are hauled up in sets by the winch into the rotary framing rotatably supported with a predetermined inclination, and they are rolled over under pull of the rope so that any securing device for the tubs can be dispensed with, avoiding trouble of setting or engaging the devices. In addition, the present invention has also an advantage in that not only safe and quick operation but wholly automatic handling of the coal tubs is obtained.

Further, according to this invention, an endless chain 10 passes, as described above, around the sprocket 5 or the wave-shaped teeth of the sprocket ring 6, of large diameter, secured to the outside of the rotatory framing A and around the sprocket wheel 9, of small diameter mounted on the axle of the driving electric motor, so that the velocity of revolution of the motor is properly reduced through the smaller sprocket wheel 9 and the rotatory framed structure A can be freely turned either clockwise or counterclockwise. Further, according to

this invention, when the rotary framing is stationary, that is, in the normal position, the chain 10 sags, in the lower portion thereof as shown in Fig. 7. In turning of the rotary framing together with the tubs inside, the lower portion of the chain 10 is tightened up so that the chain runs lightly whereby the rotary framing is allowed to turn or return smoothly. Accordingly, the starting of the rotary framing is simple and there is no fear of breaking the chain or overloading the electric motor. 5 When the rotary framing goes around to roll the tubs over, the shock due to the rolling over of the tubs is relieved by tightening of the sagging in the upper portion of the chain. When returning the rotary framing after the tubs therein have been emptied, the electric motor 10 runs lightly at first until the sagging part of the chain or its upper portion tightens up, and the resistance of the framing comes to act on the motor through the chain. Thus, according to the invention, an easy and accurate operation is always effected, insuring smooth starting and returning motion of the rotary framing with no extraordinary load falling on the chain and without any motor trouble arising.

Further, the tippler according to the present invention may be applied to the mineral ores and the like in a same 25 manner as above described.

What I claim is:

1. A tippler system, for unloading tubs movably supported by wheels upon rails, comprising an inclined rail section for guiding said tubs, a rail extension independent 30 from said inclined rail section but normally continuing therefrom, a rotary element supporting said rail extension and adapted to rotate about an axis parallel to said inclined section to swing said rail extension in a circular path about the axis, a bin positioned beneath said rotary 35 element, a winch for pulling a plurality of tubs up said inclined rail section onto said rail extension an electric motor powering said winch, first means for initiating the operation of said motor and for terminating the operation thereof with a plurality of tubs positioned on said rail extension, and second means for rotating said rotary element whereby the contents of said plurality of tubs is emptied into said bin; said rotary element comprising spaced circular and coaxial members, a framework rigidly affixed between said spaced members and supporting 40 said rail extension, a peripheral protrusion on one of said spaced members, spaced grooved rollers engaging said protrusion for the rotation of the associated member about said axis, teeth spaced about the periphery of the other of said spaced members, spaced grooved rollers for 45 accommodating said teeth for the rotation of the associated member about said axis, a chain coupled between said second means and said teeth for the rotation of said rotary element, and anti-thrust rollers for preventing axial displacement of said rotary element.

2. A system as claimed in claim 1 wherein said first means comprises a manual switch for initiating the operation of said motor and a limit switch for terminating the operation of said motor with the plurality of tubs in position on said rail extension.

3. A system as claimed in claim 2 wherein said limit switch is responsive to said winch for terminating the operation of said motor.

4. A system as claimed in claim 2 wherein said second means comprises a motor for driving said chain and 65 a limit switch for initiating the operation of said motor with said plurality of tubs in position on said rail extension.

5. A system as claimed in claim 4 wherein said inclined rail section is inclined between two and three degrees.

6. A system as claimed in claim 5 comprising a side track and a self-operating switch for switching emptied tubs onto said side track.

7. A system as claimed in claim 6 wherein the chain 70 between said second means and said teeth is an endless

chain one branch of which is loosely connected between
said second means and said teeth.
